ALBERT S. ROSS, OF DALLAS, TEXAS, ASSIGNOR TO O. R. SEAGRAVES, OF HOUSTON, TEXAS

ARTICLE HANDLING DEVICE

Application filed March 24, 1930. Serial No. 438,273.

This invention relates to dispensing machines.

The conventional coin controlled machine of this type embodies an ejector and an actuator adapted to be operatively connected together by a coin deposited in the machine.

Dispensing machines of the money changer type are designed to eject a predetermined number of change coins after the deposit in the machine of the coin to be changed. The number of change coins dispensed depends upon the thickness thereof. Change coins of the same denomination vary in thickness, and the machines now in use are defective in that they dispense too many relatively thin coins. This invention has for one of its principal objects the provision of new and improved means whereby only a predetermined number of change coins will be dispensed even though some or all are relatively thin.

Other objects will hereinafter appear.

The preferred embodiment of the invention in the form of a money changer is illustrated by the accompanying fragmentary drawings, of which Fig. 1 is a vertical sectional view from one side of the machine; Fig. 2, a vertical sectional view from one end of the machine; Fig. 3, a detail horizontal view taken from the line 3—3 of Fig. 1; Fig. 4, a vertical sectional view from that side of the machine opposite to the side indicated by Fig. 1; Figs. 5 and 6, detail vertical and horizontal views, respectively, illustrating the connection between the actuator and the ejector; Fig. 7, a detail vertical view in section of the preferred embodiment of the ejecting means; Fig. 8, a horizontal view on the line 8—8 of Fig. 7, and Fig. 9, an enlarged vertical detail of said ejecting means.

The operative parts of the machine are shown mounted within a suitable casing 1 provided with a coin deposit slot (not shown), a change chute 2 to direct change to an accessible tray, not shown, and a coin receptacle 3 (Fig. 1). The partition plates 4 and 5 (Fig. 2) extend parallel with one side wall of the casing and adjacent thereto. The floor 6 extends transversely of the casing and serves to support the guide 9 for the change ejector

7, which ejector (Figs. 2 and 4) is reciprocable immediately under the magazine 8, and is provided with an opening 7b for the reception of a predetermined number of coins at the bottom of the stack of coins.

The actuator (Figs. 1 and 2) includes a lever 10 pivoted at 41 and having an arm 10a extending through a slot 1a to the exterior of the casing. The arm 10a may be provided with a knob (not shown) to be grasped by the operator. The other arm 10b of the actuator extends downwardly and is connected to the reciprocable member 11 by the head and socket joint 10c. The member 11 carries a pair of coin-actuating lugs 11a which extend outwardly through slots 4a in the partition plate 4, as shown particularly by Figs. 1 and 2.

The ejector carries a coin-actuated pin 7a which fits in slots in the guide 9 and which extends outwardly through a slot 11b in the member 11 and a slot 4b in the partition plate 4. See Figs. 1, 2, 5 and 6.

Deposited coins pass downwardly in a suitable passageway, not shown, between the plates 4 and 5, and are thereby directed into the operative position C between the actuating lugs 11a and the actuated lug 7a, as shown clearly by Figs. 1 and 2.

It will be obvious that when the coin C is so positioned and the arm 10a of the actuating member is depressed by the operator, the sliding member 11 will be moved to the right (Figs. 1, 5 and 6), carrying with it the lugs 11a which will force the coin C to the right and cause the coin to force the lug 7a and the ejector 7 to the right. The predetermined number of change coins within the opening 7b (Fig. 4) will be carried over and dropped through the change opening 12 into the change passageway 2 through which they will pass to the tray, not shown. It will be understood that if the actuator is moved when no operative coin is between the lugs 11a and 7a, the ejector 7 is not moved because the lugs 11a pass on either side of the lug 7a.

The means to insure the ejection of only the proper number of change coins, even though such change coins are relatively thin, will now be described. The preferred embodi-

ment of said means is illustrated by Figs. 7, 8 and 9, and is unlike that disclosed in the other figures.

In Figs. 7, 8 and 9, the coin magazine is indicated at 8' and is rigidly fixed to the base 14 which has a coin opening 14a. Pivoted in the base 14, as indicated at 16, is a coin detaining member 15. The forward end of this member is forked as indicated at 15a and beveled as indicated at 15b and extends about the opening 14a. The ejector 7' is of a vertical thickness less than the distance between the upper surface of the floor 6' and the lower surface of the base 14; so that the clearance between the upper surface of the ejector 7' and the lower surface of the base 14 is substantially equal to one-half of the thickness of a change coin of normal size. In the apparatus shown, the distance between the upper surface of the floor and the lower surface of the base is equal to five times the thickness of a change coin of normal size; and the vertical thickness of the ejector 7' is therefore substantially equal to four and one-half times the thickness of a change coin of normal size. The lower edges of the ends of the arms of the forked member 15 and the upper surface of the ejector 7' are in the same horizontal plane.

Now if five change coins of normal thickness enter the opening 7b', the uppermost of said coins will be partly in said opening, and if the ejector is actuated to move said five coins from under the stack, the uppermost of said five coins will be carried forward and will strike the beveled portion 15b of the coin detaining member 15 and move the adjacent end of said member upwardly out of the way. The member 15, it will be understood, is rocked about its pivot 16. So the said five coins are carried over the opening 12' and dropped therethrough into the change chute.

On the other hand, if five relatively thin change coins 60 (Fig. 9) enter the opening 7b', the sixth coin 61 resting on top of the uppermost of said five coins will not be discharged with the five coins because the lower surface of the sixth coin 61 will be below the lower surface of the base 14, but above the upper surface of the ejector 7', and the five relatively thin coins 60 will be moved by the ejector 7' from underneath the sixth coin and dropped into the passageway 12', the sixth coin being detained by the member 15. When the ejector returns to its normal position, the sixth coin will then drop into the opening 7b', together with the predetermined number of additional coins.

It will be apparent from the foregoing that the coin detaining member 15 does not interfere with the ejection of five coins of predetermined thickness because it is movable out of the path of the uppermost of said coins when said uppermost coin is forced

forward by the ejector 7'; and that it prevents the ejection of six thin coins because the uppermost of said thin coins is not engaged by the ejector 7' but merely rests upon the coin below it, and the coin detaining member 15 is, therefore, not moved out of the path of the uppermost of said thin coins. The uppermost of said thin coins remains in place under the stack of coins above it while the five thin coins below it are ejected.

Referring now to the means to insure the release of the operating coin C after it has performed its function, the apparatus includes (Figs. 2 and 4) a lever 17 pivoted as indicated at 18 and having a forked lower end 17a for the reception of the head 7c carried by the ejector 7. Connected to the lever 17 at 19 and to the fixed bracket 20 at 21 is the spring 22. Referring particularly to Fig. 4, when the ejector 7 is manually moved to the right by means of the operating lever 10, and the point 19 is moved slightly to the right of the plane passing through the points 18 and 21, the spring 22 then rotates the lever 17 in an anti-clockwise direction on its pivot 18 to cause said lever to move said ejector into its ejecting position. And so the actuating lugs 11a cause the coin C to move the actuated lug 7a until the lever 17 is rotated to that position from which it may be rotated in an anti-clockwise direction by the spring 22, whereupon the spring actuated lever carries the ejector forwardly away from the manually movable actuator. The lug 7a is therefore moved away from the lugs 11a and the coin C therebetween is released and permitted to drop through the slot 23 into the coin box 3.

The spring 22 yieldably holds the ejector in its ejecting position until the operating handle is released. The spring 50, which is connected to the casing at 51 and to the sliding member 11 at 52 (Fig. 1) thereupon moves the sliding member 11 back to its normal position (to the left in Figs. 1, 5 and 6). The ejector 7 does not accompany the member 11 on the initial part of the return movement, and the consequent separation of the lugs 11a and 7a insures release of the coin, so that said coin cannot be used again to obtain change. When the end wall 11b' (Figs. 5 and 6) of the slot in member 11 engages the pin 7a, the resistance of the spring 22 is overcome and the ejector is moved in the same direction toward its normal position. When the ejector completes a predetermined part of its return movement, the point 19 (Fig. 4) is carried to the left of the plane passing through the points 18 and 21, and the spring 22 then moves the ejector to its normal, inactive position, and yieldably holds it there so that the ejector cannot be moved into its ejecting position by tilting the machine.

The preferred embodiment of the means

to prevent premature retrograde movement; that is, return movement of the actuator to its normal position before it has completed its ejecting movement, is illustrated by Figs. 1 and 3. It includes a pawl 24 pivoted to the lever 10 as indicated at 25 and having a tooth 24b to engage a rack 26. Mounted above and adjacent the pawl is a pivoted switch 27 held in the position shown by Fig. 1 by a stop pin 28. The pawl carries a pin 24a.

Now when the lever 10 is rotated in an anti-clockwise direction about its pivot 41 to cause ejection of the change, the arm 10b is swung to the right. The tooth 24b of the pawl jumps over the teeth of the rack 26. The pin 24a then strikes the switch 27 and moving it upwardly out of the way, moves to the right of it. The switch then resumes its normal position. When the lever 10 then swings in a clockwise direction back to its normal position, the pin 24a rides upwardly on the switch 27, so that the pawl in its return movement is elevated above and kept out of engagement with the teeth of the rack 26 until it drops from the pivot 29 of said switch. The path of the pin 24a is indicated by the arrows in Fig. 1. It will be obvious that the engagement of the tooth 24b with the teeth of the rack 26 will prevent return of the lever 10 to its normal position until after the ejecting movement has been completed.

The machine will therefore dispense only the proper number of change coins even though some or all are relatively thin; an operator cannot make it dispense change by tilting it; and no more than the predetermined change can be obtained from it by the use of a given operating coin.

The invention is not limited to the embodiments shown. Various changes may be made within the scope of the following claims.

I claim:

1. A dispensing machine having an article magazine, an article ejector, and an excess article detaining member movably mounted adjacent said magazine and ejector.

2. A dispensing machine having an article magazine, an article ejector adapted to receive from said magazine and eject a predetermined number of articles of predetermined dimensions, and an excess article detaining member movably mounted adjacent said magazine to prevent the ejection of a greater number of smaller articles.

3. A dispensing machine having an article magazine, an article ejector spaced from and slidably transversely with respect to said magazine, and an excess article detaining member movably mounted adjacent said magazine and normally extending into the space between said magazine and said ejector.

4. A dispensing machine having an article magazine, a floor beneath said magazine to support articles stacked in said magazine,

an ejector slidable on said floor and spaced from said magazine, and an article detaining member movably mounted adjacent said magazine and normally extending into the space between said magazine and said ejector.

5. A money changer having a change magazine, a change ejector spaced from and slidably transversely with respect to said magazine, and an excess change coin detaining member movably mounted adjacent said magazine and having a forked end normally extending into the space between said magazine and said ejector.

6. A money changer having a change magazine, a floor beneath said magazine, a change ejector slidable on said floor and spaced from said magazine, and an excess change coin detaining member movably mounted adjacent said magazine and having a forked end normally extending into the space between said magazine and said ejector.

7. A money changer having a change magazine, a change ejector slidable beneath said magazine and adapted to eject a predetermined number of change coins of normal thickness, and a detaining member movably mounted above said ejector and adjacent said magazine to prevent the ejection by said ejector of a greater number of relatively thin coins.

In testimony whereof I hereunto affix my signature.
